UNITED STATES PATENT OFFICE

HARRY D. LATHROP, OF CHICAGO, ILLINOIS

CAN WASHING MACHINE

Application filed January 26, 1927. Serial No. 163,819.

This invention relates to improvements in can washing machines of the type in which the cans are advanced step by step through successive cleansing operations, and the primary object in view is the simplification of the actuating and controlling mechanism, and the increasing in effectiveness of operation.

A further object is the utilization of the same source of power for actuating the step by step advancing mechanism, and for effecting ejection of the cleansing fluids, whereby the cans are assured of being in operative relation to the cleansing jets during operation of such jets, and the cessation of such jet operations assured during relative movement of the cans.

With these and further objects in view, as will in part hereinafter be stated and part become apparent, the invention comprises a can carriage, fluid actuated means for shifting the carriage, a by-pass for the fluid, and means for the controlling discharge of the fluid through the by-pass and directing the same into cleansing relation to the cans.

The invention also comprises other novel constructions, combinations and arrangements of parts, as will hereinafter be stated and subsequently pointed out in the claims.

In the accompanying drawings,

Fig. 1 is a view in side elevation of a machine embodying the features of the present invention.

Fig. 2 is an end elevation thereof, looking at the charging end.

Fig. 3 is a horizontal section taken on the planes indicated by line 3-3 of Fig. 5 and looking downward, the parts beneath being seen in the plan.

Fig. 3^a is an enlarged, detailed, horizontal section through the water heating apparatus and connections, the connections being broken.

Fig. 4 is a longitudinal, vertical section taken substantially on the plane indicated by line 4-4 of Fig. 3 and looking toward the front side of the machine.

Fig. 5 is a transverse vertical section taken substantially on the planes indicated by line 5-5 of Fig. 3, and looking in the direction

shown by the arrows, parts being broken away for the saving of space, and the parts being shown on an enlarged scale.

Figs. 6 and 7 are fragmentary vertical sections taken substantially on the planes indicated by lines 6-6 and 7-7 respectively of Fig. 3, and looking in the directions shown by the arrows.

Fig. 8 is an enlarged, detailed, sectional elevation of the fluid operated carriage actuator.

Fig. 9 is a top plan view of the upper hot water jets detached.

Fig. 10 is a similar view of the upper detergent solution jets.

Referring to the drawings by numerals, 5 indicates an appropriate frame, preferably in the form of a rectangular skeleton made up of angle bars and including vertical standards 6-6 for the upstanding rear plate. For convenience of identification of relative directions, that part of the machine seen at the left in Fig. 3 will be designated the "charging end" and the opposite end will be known as the "discharging end," 70 while the parts in the foreground of the figure will be referred to as the "front" side of the machine, and the opposite side as the "back."

Within the frame 5 is mounted tank 7, 80 which is divided by partition plate 8 into compartments 9 and 10 for the purpose of preventing intermixture of certain of the cleansing solutions.

Mounted on and fixed to the main portion 85 of frame 5 is a pair of guide rails 11, preferably in the form of angle bars, and between the rails 11 is arranged a carriage 12. The carriage 12 is preferably made up of longitudinally disposed parallel spaced angle 90 bars 13-13 rigidly connected together by cross-plates 12' 12'. Extending parallel to and spaced from the vertical web of each angle bar 13 and upstanding from the horizontal web thereof is a flat bar 14, which is bolted or otherwise appropriately fixed to the vertical web of the respective bar 13. The upper edges of the vertical webs of bars 13 and 14 are disposed below the horizontal 95 plane of the upper edges of bars 11, so that 100

a can may rest on bars 11 without touching carriage 12, as clearly seen in Fig. 7. Each pair of bars 13 and 14 forms a relatively narrow channel, and, within said channels, 5 can-feeding detents or dogs 13' 13' are pivoted, as best seen in Figs. 4 and 7. As a matter of convenience of construction, the bolts which anchor the bars 14 to the bars 13 may be utilized as the pivots for the dogs 10 13'. Each dog 13' is pivoted at a point in its length at one side of the middle, which causes one end to normally rest by gravity upon the floor of the channel in which the dog is pivoted, that is, the upper surface of 15 the horizontal web of the respective angle bar 13, the lower end portion of the dog thus acting as a weight to retain the upper end portion upstanding above the channel and above the plane of the upper edges of bars 20 11 in position to engage successive cans. Each dog 13' will remain with its shorter end portion raised during a feeding step of carriage 12, but freely pivots downward when necessary during reverse movement of 25 the carriage.

Carriage 12 is mounted to reciprocate freely within those limits represented by the distance somewhat greater than a step in the step by step progress of a can passing 30 through the machine in the process of being cleansed. The actual distance of advance of a can is governed by the effective travel of the pair of dogs 13' after the dogs have engaged the can. Antifriction supports are 35 provided for the carriage, and preferably consist of pairs of rollers 15-15 arranged near the end portions of and beneath the carriage, each pair being connected by an axle or shaft loosely journaled in a pair of 40 pendent U-brackets 16, 16, fixed to the under-surfaces of the rails 11-11 near the end portions thereof. Rails 11 extend beyond the frame 5, as clearly seen in Figures 3 and 4, at the charging end of the machine for receiving 45 successive cans to be engaged by dogs 13' and slid along rails 11 for advancing them to the successive cleansing positions. At the discharge end, a receiving shelf 17 is provided for the delivery of discharged, 50 cleansed cans.

The reciprocations of the carriage 12 are effected through the employment of a fluid motor to move the carriage through the advance step, and a counter-balance to return 55 the carriage when released by the motor. As best seen in Figs. 2 and 3, a hydraulic pump 18 is preferably mounted on the frame 5 at the back of the tank 7, and may be connected to any appropriate source of power, 60 such as the electrical motor illustrated. Arranged in the compartment 10 of tank 7 is a feeder pipe 19, which communicates with the intake side of the pump 18. A discharge pipe 60 leads from the pump 18 and communicates with the cleansing fluid discharge

pipe 36 directly, and with a discharge pipe 22 past a by-pass valve 20. The valve 20 is of the common commercial type constructed to resist opening up to a previously determined pressure and then to open and permit 70 flowing of the pressure fluid as the pressure rises to and above the predetermined point. It is customary to adjust such by-pass valves according to the pressure required. In the present instance, 35 lbs. per square inch has 75 been found a very efficient pressure at which to set the valve 20. Thus, when the fluid may discharge through pipe 36 freely, so that the pressure at the valve 20 is below that at which the valve leaves its seat, there 80 will be no pressure from the pump 18 to the pipe 22, but, when the free discharge through pipe 36 is cut off, the rising pressure at valve 20 will effect the opening of the valve and consequent discharge of the pressure fluid through the pipe 22. A bleeder port 22' leads from the pipe 22 and discharges into compartment 10 of tank 7. The pipe 22 is provided with a hand-operated control valve 22^a, and the bleeder port 90 22' is provided with a similar valve 22^b.

As best seen in Figs. 3, 4 and 5, a cylinder 21 is arranged longitudinally of and fixed to one of the rails 11, as by rigidly connected brackets 23-23 anchored to the respective rail 11 and to the respective ends of cylinder 21. As best seen in Figure 8, a piston 23' is located within the cylinder 21, and has a piston rod extending through an appropriate gland at the end of the cylinder and beyond the cylinder, and being rigidly fixed to a bracket 25, which, in turn, is connected directly to the carriage 12. The free terminal portion 24 of the piston rod, extending beyond the bracket 25, is provided with a buffering cap 51 for the purposes hereinafter stated. The pipe 22, as clearly seen in Fig. 3, leads from the discharge side of by-pass 20 to the intake end of the cylinder 21, so that when the valve 20 is open, 110 pressure fluid acts on the piston 23' to actuate said piston and the carriage 12 for moving the carriage in the direction of advance. After completion of the advance stroke of piston 23' discharge through pipe 115 36 is permitted, by apparatus hereinafter described, which causes the relaxing of pressure on valve 20 and permits the seating thereof, so that piston 23' is no longer under pressure. Thereupon, the liquid from the cylinder 21 begins to flow back through the pipe 22 and out through the bleeder port 22'. A cable 26 is anchored to the carriage 12 at one end of the cable and is threaded over grooved pulley 27, and at the other end anchored to the pendent weight 28, as best seen in Figs. 1, 2 and 3. Pulley 27 is carried by an appropriate shaft journaled in brackets carried by the bars 11. As soon 125 as the pressure is relaxed from piston 23', 130

the counter-balance stress of weight 28 begins to return carriage 12 to its initial position. Incident to such return, the piston 23' is returned to its initial position approximately at the end of the cylinder 21 with which pipe 22 communicates, and the carriage 12 is thus restored to its starting point ready for the next reciprocation. The bleeder port 22' functions at all times, but is of sufficiently small cross-sectional area to avoid interference with the delivery of the requisite pressure to the piston 23'. The valve 22^a is opened to the extent required for effecting that speed of stroke of the piston 23' found most desirable from a consideration of the most effective rate at which the carriage 12 should advance for satisfactory work. Also, the valve 22^b is set to control the effective cross-sectional area of the bleeder port 22', whereby, through the reaction or resistance to discharge of liquid through valve 22^b, the speed of the return stroke of the carriage may be controlled with precision. The valves 22^a and 22^b, therefore, enable effective governing of the speed of travel of the carriage 12. It is, of course, desirable ordinarily to have the piston 23' move relatively quickly for the advance step of carriage 12, as the cleansing operations are suspended, as will be herein-after made clear, during such advance stroke, but the return stroke is preferably ordinarily slowed down to the extent found desirable incident to the fact that all cleansing operations occur only during and subsequent to this stroke and before the beginning of the next advancing stroke.

For the purpose of confining and restricting the several cleansing fluids being directed against the cans being washed, a hood 29 is arranged above carriage 12, and is supported by a rock shaft 31, journaled in bearings 32, attached to the upper end portions of standards 6. The back side of the hood 29 is open, the several enclosing chambers for the cans being completed by the back wall or plate 6' rigidly carried by the standards 6. Transverse, vertical partitions 33 are arranged in hood 29 for dividing the same into can containing chambers or compartments. Counter-balancing arms 34 are fixed to the hood 29 and outstand beyond the axis of the pivot 31 and are weighted at 34' sufficiently for equalizing the weight of the hood 29, so that the hood will remain in a raised or lowered position when moved manually to such positions.

The present improved mechanism is designed for expeditiously and effectively cleansing successive cans, and, to this end, successive cleansing agents are delivered to the cans as they are advanced by the successive reciprocations of carriage 12, one reciprocation being proportioned in extent to effect movement of a can from a position

in one compartment in the hood 29 to a corresponding position in the next compartment. Provision is made for the delivering to the interior and exterior of the cans, while in successive positions, of cold water, 70 cleansing sodium or other detergent, hot water and steam successively.

In Figs. 4, 5 and 7, a can to be cleansed is indicated in dots at 61, the can being seen in an inverted position. A cold water supply pipe 42, leading from the city main or any other appropriate source of cold water supply, extends to a reciprocating, spring-seated valve 46, whose stem extends upwardly through an appropriate gland and 80 has its upper end engaged by an operating lever 48, pivoted, at one side of the valve stem, to a bracket 47, anchored to the valve housing. Communicating with the discharge end of valve 46 is the discharge 85 pipe 44 leading to vertically upwardly discharging jet 43. The jet 43 is located between the rails of the carriage 12 in position for projecting a stream upwardly under considerable velocity into the can 61 resting 90 on the rails 11.

A drip pan 62, as best seen in Fig. 7, preferably surrounds the lower end portion of the tube of jet 43 at its juncture with pipe 44, and the parts may be clamped together with an appropriate nut 63 threaded onto jet pipe 43 and engaging the bottom of pan 62 and clamping the same against the upper terminus of the fitting of pipe 44, communicating with the jet tube 43. For the purpose of rigidity, the pan 62 may also be secured by bolts 64-64, extending through the horizontal flanges of the rails 11, a spacer sleeve 65 being located about each of the bolts 64 and of a length to be 100 clamped between the upper surface of the bottom of pan 62 and the lower surface of the horizontal flange of the respective rail 11. The pan 62 will serve as a settling pan for the collection of solids dislocated from 110 the can 61 by the stream from jet 43.

A branch pipe 42^a leads from the pipe 42 through the wall of tank 7 and is preferably provided with a downturned discharge end portion 42^b in chamber 10 of tank 7, so as 115 to deliver a supply of water to the tank when required. A hand control valve 42^c is arranged in the length of the branch pipe 42^a for shutting off the delivery to the tank 7.

A steam pipe 37 extends from any appropriate source of supply, (not illustrated) and communicates with a valve 46^a having a controlling and actuating lever 48^a, similar in construction and operation to valve 46 125 and lever 48, and pivoted to a similar bracket 47^a. Leading from the discharge side of the valve 46^a is a pipe 37^a, which extends along and within the housing of the tank 7 to a point beneath the center of the final 130

location of a can to be cleansed prior to its discharge from the machine. Pipe 37^a terminates in an upwardly directed steam jet 41 located in the line of the axis of a can 61 when in the final compartment of the 5 series of compartments of hood 29.

The steam pipe 37^a, near the valve 46^a, is provided with a branch 40, which discharges into the heating chamber 45, as 10 best seen in Figures 3^a and 4. The cold water supply pipe 44 is provided with a branch 44^a, which leads laterally into the heating chamber 45, as seen in dotted lines in Fig. 3, in full lines in Figs. 4 and 5 and 15 in detail in Fig. 3^a. The pipe 44^a preferably enters chamber 45 through its side wall, while the pipe 40 approaches the chamber longitudinally and communicates through the end of the chamber by an injector or 20 discharge nozzle 40^a having a tapered tip 40^b surrounded by a nozzle hood 40^c, providing a relatively small annular space 40^d about the extremity of the tip 40^b. The hood 40^c enables the surrounding column of 25 water to initially absorb a certain degree of heat from the approaching steam before the actual mixture of the steam with the water. The steam is thereby more or less reduced to a vapor, so that the reactive resistances 30 of steam discharging into water is avoided and the required supply of steam permitted to enter the chamber 45 sufficiently freely and rapidly to raise the temperature of the water within the chamber 45, and particu- 35 larly near the discharge end thereof to the required degree of heat before discharge of the water through the outlet pipe 38, which leads from the chamber 45, preferably in alignment with the nozzle 40^a. A jet or 40 nozzle 39 upstands from and communicates with an intermediate portion of pipe 38, and is arranged to discharge upwardly substantially in the line of the axis of a can located in the next to the last compartment 45 of hood 29.

The pipe 38 extends beyond the jet 39, as best seen in Figs. 3 and 6, and is turned upward and branched at 35. Upstanding from the free ends of the branch 35 are 50 pipes 35^a. As a matter of convenience of mechanical construction, unions 35^e are interposed in the length of pipes 35^a, preferably near the point of communication thereof with pipe 35. The pipes 35^a are located 55 adjacent and immediately in front of the back plate 6', and are spaced lengthwise of the machine a distance equal to nearly the width of the respective chamber of hood 39, the pipes 35^a being located within the third 60 of said chambers counting from the charging end of the machine. The pipes 35^a thus extend along and within the vertical angles at the back portion of hood 39 formed by the respective hood partitions and the back 65 plate 6', and each pipe 35^a is provided with

a series of apertures 35^b for occasioning the jetting of the hot water, and said apertures are located to cause the jetting water to flow in a direction toward the axis of the can within the particular chamber of the hood 29. The pipes 35^a, as best seen in Fig. 9, are connected at their upper ends by an equalizing pipe 35^c, and spaced forwardly of each pipe 35^a is a pendant jet pipe 35^d, the latter pipes being connected at their upper ends by pipes 35^e with the respective pipes 35^a. 70 Pipes 35^d, as clearly seen in Fig. 4, are closed at their lower ends and provided along their lengths with jet openings 35^f directed to cause the flow of jetting water toward the axis of the can within the chamber of hood 29 occupied by pipes 35^a and 35^d. The pipes 35^d are located in the vertical angles of said chamber at the front side of the chamber and are spaced from the pipes 35^a sufficiently for the passage of a can between the two sets of pipes during its advance through the machine.

The steam supply pipe 37 is formed with a branch 37^b leading into the lower portion of the chamber 10 of the tank 7 and valved at 37^c, so that the contents of chamber 10 may be supplied with steam should it become desirable to raise the temperature thereof. The partition 8 is provided with a valved port 8^c communicating between chambers 9 and 10, so that, when desired, communication may be established between said chambers. Discharge pipes 66 lead from the respective compartments of tank 7 and are valved at 66' for convenience in draining and cleaning out.

In operation, the sodium solution or other detergent is drawn by pump 18 from tank 7 through pipe 19 and discharged from the pump through the pipe 60 and branch 36 when free to discharge therefrom and otherwise past the valve 20. The pipe 36 leads in any appropriate manner to the front side of the machine and there communicates through a valve 46^b, similar in construction, arrangement and operation to valve 46, and provided with a control lever 48^b pivoted to a bracket 47^b for actuation of the valve after the manner of the operating of valve 46. The discharge side of valve 46^b, as best seen in Fig. 5, communicates with a pipe 67, extending to a point beneath carriage 12 and there provided with an upstanding and upwardly discharging jet 68 arranged to discharge substantially in the line of the axis of a can while in the second compartment of hood 29. The pipe 67 extends beyond jet 68 and is branched at 69, the free ends of the branch communicating with upstanding pipes 70 similar in construction and arrangement with pipes 35^a. As a matter of mechanical convenience of construction, each pipe 70 is provided with a union 71 in its 110 115 120 125 130

length, preferably near the place of communication of branch 69. The pipes 70 are arranged at the back side adjacent the back-
 5 ing plate 6' and are spaced lengthwise of the machine, so as to stand substantially in the vertical angles of the third compartment of hood 29. Each pipe is provided with jet openings 72 located to direct the streams toward the axis of the can within the par-
 10 ticular hood chamber. As best seen in Figs. 5 and 10, the upper ends of the pipe 70 are connected by pipe 73, and each pipe 70 is provided with a forwardly extending horizontal pipe 74, which, in turn, communi-
 15 cates with a pendant jet pipe 75, the pipes 75 being spaced from pipe 72 approximately for the width of the particular hood chamber, so that cans may pass between the two sets of pipes. The pipes 75 are also spaced
 20 longitudinally of the machine sufficiently to lie substantially in the angles of said hood chamber at the front side of the machine. An equalizing pipe 76 connects the upper ends of the pipes 75 and, as a convenience of me-
 25 chanical construction, a connection may be effected by the use of a long thread 77 and a jamb nut 78 at one end of the pipe 76. Each of the pipes 75 is formed with jet openings 79 located for directing the streams toward
 30 the axis of the can within the particular hood chamber. Pipes 75 are capped or otherwise closed at the lower end.

The several levers 48, 48^a and 48^b project through vertical slots 49 in the frame 5 and extend to a point in the path of movement of the forward, lower edge of hood 29 in coming to a seated position, the relation of the parts being such that, when the hood is seated, its said edge, as clearly seen in Fig. 5, rests upon and depresses the levers 48, 48^a and 48^b, and thereby holds open the several valves 46, 46^a and 46^b. As soon as the hood is raised, the springs within the valves themselves (not illustrated) return
 45 the valves to a seated position and proportionately elevate the valve operating levers.

In order to lock the hood 29 in the closed position during each separate cleansing operation, a keeper 50' is rigidly fixed to frame 5 and extends horizontally beneath the charging end portion of the hood 29, as seen in Figs. 2, 3 and 4. A pendent, freely pivoted, latch 50 is carried by the hood 29 and tapered to slide past keeper 50' as the hood is coming to a closed position, the detent of the latch 50 falling into a locking position beneath the keeper 50' just as the hood 29 reaches its fully closed position. The lower end portion of the latch 50 is in line with the axis of piston 23', so that when a return stroke of the carriage 12 occurs, incident to the travel of the piston 23', the extended portion 24 of the piston rod causes the abutment 51 thereof to contact with the lower end portion of latch 50 and swings

the same free from keeper 51, so that the hood may be swung freely to its elevated position, as seen in dotted lines in Fig. 2. For convenience in the manual swinging of hood 29, an appropriate handle 53 is fixed to a lower portion of the hood and outstands laterally therefrom, as seen in Figs. 1 and 2, to a convenient point of access for the operator.

The operation of the machine may be briefly stated as follows: A can is placed on the protruding charging end of rails 11, hood 29 is elevated, and pump 18 is started. The hood being raised, the valves 46, 46^a and 46^b will be closed, and the pressure from pump 18 will, therefore, open the valve 20 and allow the fluid to pass through pipe 22 to the cylinder 21, a negligible portion unavoidably escaping through the bleeder 22'. The movement of the piston 23', incident to the ingress of the pressure fluid, causes the carriage 12 to travel toward the discharge end of the machine a distance slightly greater than a step of advance of a can, so that the parts reach the position seen in Figs. 3 and 4. During this movement of carriage 12, the charging end pair of dogs 13' will have engaged the can 61 on rails 11 and slid the can along the rails to the new position where it rests on rails 11 while carriage 12 is making its return. In this position, the can is in line with the first compartment of hood 29, and will be disposed approximately axially above the cold water jet 43. The hood is then lowered, and in reaching its closed position, depresses levers 48, 48^a and 48^b, and thus effects discharge through all of the lower jets 43, 68, 39 and 41 and also all of the exterior jets provided in pipes 35^a, 35^b, 70 and 75. Of course, the second, third and fourth chambers of the hood will as yet be empty, but after the machine has reached the fourth operation, all of the hood chambers will be filled with cans in the various stages of being cleansed, and the operation will continue with the machine thus filled, one can being discharged from the machine and one can being charged into the machine with each operation. As soon as the valve 48^b is open, so that there is a free discharge from the pipe 36, the pressure will drop sufficiently at valve 20 to allow said valve to take its seat. The pressure in pipe 22 thereupon ceases, and the bleeder 22' allows the discharge of the fluid from the cylinder 21. The valve 22' is important in that its location will effectively control the speed at which the weight 28 may pull the carriage 12 and the piston 23' back to the starting point. Such control also governs the length of time of the cleansing operation. The carriage thus returns under the action of weight 28, while the can remains in the first chamber of the hood 29. As the piston 23 is reaching its initial posi-

tion, the abutment 51 strikes latch 50 and releases the same. This is a signal to the operator to raise the hood. If he neglects to do so, the parts will remain stationary with the several cleansing fluids continuing to jet. As soon as the hood is raised, the jetting ceases, as the valves 46, 46^a and 46^b close instantly. Valve 20 opens and a second stroke of the carriage 12 begins. The second can will have, in the meantime, been placed on the charging end of rails 11, and will be advanced by dogs 13' to the position above jet 43, while the first can advances to a position above jet 68 and in the location for being within the second chamber of hood 29 when the hood is closed. The dogs 13' 13' effectively advance the cans with the advance movement of the carriage, but freely depress and escape the cans on the return movement, leaving the cans in their advanced positions.

When the first can has reached the position of the second hood chamber, the operation will be repeated by the lowering of the hood as above described, and the can will be subjected interiorly and exteriorly to the jet of detergent fluid. The next step of operation is a repetition of that above described, involving on the part of the operator the raising of the hood as soon as the latch 50 is again released, a third can being supplied to the carriage. The first can will now be moved into position above the jet 39, and the hood lowered to subject the cans to the cleansing jets. Hot water is thus discharged against the interior and exterior of the first can to rinse same thoroughly. It is to be noted that while there is no control valve for the hot water jets, the discharge of hot water through jet 39 and the jets of pipes 35^a and 35^d is effectively governed by the combined action of the valves 46 and 46^a, since the discharge of cold water and of steam into the heating chamber 45 controls the delivering of hot water to said jets. With the next step in the operation, a fourth can is added by being placed on the extended ends of rails 11 at the charging end, and the first can is advanced to the position above the steam jet 41, which injects steam to the interior of the can adequately for thoroughly sterilizing the same. With the next complete step of the machine, the first can will be discharged onto the platform 7, and the machine will continue thus in full operation.

What is claimed is:

1. A receptacle cleaning apparatus comprising in combination an intermittently movable carriage for shifting receptacles to be washed; a cylinder having a piston therein for actuating the carriage; means for transmitting fluid under pressure to said cylinder for actuating said piston; means for discharging fluid from said transmit-

ting means and utilizing it as a cleaning agent against the receptacles and thereby reducing the pressure on said piston; and a valved bleeder port for the cylinder.

2. A receptacle cleaning apparatus comprising in combination an intermittently movable carriage for shifting receptacles to be washed along a predetermined path; a cylinder having a piston therein for actuating the carriage; means for transmitting a fluid under pressure to said cylinder for actuating said piston, including a pressure-responsive valve; means for discharging fluid from said transmitting means and utilizing it as a cleaning agent against the receptacles, comprising a valve; said pressure-responsive valve being connected with said discharging means for opening said cylinder to said fluid transmitting means for actuating said piston when said discharge valve is closed.

3. A receptacle cleaning apparatus comprising in combination an intermittently movable carriage for shifting receptacles to be washed; a cylinder having a piston therein for actuating the carriage; means for transmitting fluid under pressure to said cylinder for actuating said piston including a pressure-responsive valve; and means for discharging fluid from said transmitting means in advance of said valve and utilizing it as a cleaning agent against the receptacles and thereby reducing the pressure on said valve to permit it to close.

4. A receptacle cleaning apparatus comprising in combination an intermittently movable carriage for shifting receptacles to be washed; a cylinder having a piston therein for actuating the carriage; means for transmitting fluid under pressure to said cylinder for actuating said piston; means for discharging fluid from said transmitting means and utilizing it as a cleaning agent against the receptacles and thereby reducing the pressure on said piston; means for enclosing said receptacles to be washed and movable to and from an enclosing position; valves in said discharging means and means operated by said enclosing means for opening said valves when said enclosing means is moved to its enclosing position.

5. A can washing machine comprising in combination a frame; a carriage on said frame; means carried by the carriage for shifting cans to be washed along a predetermined path; washing means arranged along said path; means for delivering a plurality of fluids under pressure to the washing means; valves for controlling the delivery of said fluids; actuating means for said carriage connected with one of said delivery means for receiving actuating fluid therefrom; and pressure-responsive valve in the connection between said actuating means and the said one of said delivery

means controlled by the pressure of the fluid being delivered through the said one of said delivery means to the washing means for governing the delivery to the carriage actuating means.

6. A receptacle cleaning apparatus comprising in combination an intermittently movable carriage for shifting receptacles to be washed; a cylinder having a piston therein for actuating the carriage; means for transmitting a fluid under pressure to said cylinder for actuating said piston, including a pressure-responsive valve; means for discharging fluid from said transmitting means and utilizing it as a cleaning agent against the receptacles, comprising a valve; said pressure-responsive valve being connected with said discharging means for opening said cylinder to said fluid transmission means for actuating said piston when said discharge valve is closed; means for enclosing said receptacles to be washed and movable to and from an enclosing position; and means operated by said enclosing means for controlling the operation of said discharge valve.

7. A receptacle cleaning apparatus comprising in combination an intermittently movable carriage for shifting receptacles to be washed; a cylinder having a piston therein for actuating the carriage; means for transmitting fluid under pressure to said cylinder for actuating said piston; means for discharging fluid from said transmitting means and utilizing it as a cleaning agent against the receptacles and thereby reducing the pressure on said piston; a valve in said discharging means; a lever for actuating said valve; a movably mounted hood for enclosing the receptacle and having a part located in contact with said lever when the hood is moved to an enclosing position for opening said valve.

8. A can washing machine comprising in combination a frame; a carriage on said frame; means carried by the carriage for shifting cans to be washed along a predetermined path; spraying means arranged along said path; means for delivering a plurality of fluids under pressure to said spraying means; a hood movable to and from a position for enclosing the cans to be washed; valves for controlling the delivery of said fluids, and means operated by said hood for opening said valves when the hood is in enclosing position.

9. A receptacle cleaning apparatus comprising a support; a reciprocating carriage mounted thereon; means for imparting intermittent movement to said carriage for moving receptacles to be washed along a predetermined path; spraying means along said path; a hood for enclosing said receptacles while being washed; said hood pivoted to be swung to and from a position to over-

lie said carriage and enclose said receptacles; pipes for supplying a plurality of fluids under pressure to said spraying means; valves in said pipes for controlling the passage of washing fluids, and means operated by said hood for opening said valves when said hood is moved to its enclosing position.

In testimony whereof I have signed my name to this specification.

HARRY D. LATHROP.
